ELECTRIC SWITCH

Hermon L. Van Valkenburg, Wauwatosa, Wis., assignor to Square D Company, Detroit, Mich., a corporation of Michigan

Application May 3, 1943, Serial No. 485,466

5 Claims. (Cl. 200—50)

This invention relates to apparatus for making and breaking electrical circuits and more particularly to enclosed electrical switches operable upon manual movement of an external operating handle.

One object of the present invention is to provide an improved construction of an enclosed electrical switch operable by an operating handle carried on an openable cover.

Another object of the present invention is to provide an improved electric switch construction.

Another object of the present invention is to provide an enclosed electric switch having improved means for effecting operation thereof.

Another object of the present invention is to provide an electric switch enclosed within a cabinet and with an improved means for effecting an operative connection between the external operating handle on the cover and the switching member of the electric switch.

Another object of the present invention is to provide, in an electric switch, improved means for effecting snap movement of the switch contacts to break an electrical circuit.

Another object of the present invention is to provide, in an enclosed electric switch, an improved construction whereby the external operating handle can readily effect movement of the switching member to break a weld between the contacts if welding should occur therebetween.

Another object of the invention is to provide an improved enclosed electric switch that is of simple construction, efficient in operation and inexpensive to manufacture.

Other objects and features of the present invention will be readily apparent to those skilled in the art from the specification and appended drawings illustrating certain preferred embodiments in which:

Figure 1 is a perspective view of the switch cabinet embodying the present invention.

Figure 2 is a front elevational view of the interior of the switch cabinet, the cover having been removed.

Figure 3 is a sectional view taken along the line III—III of Figure 2.

Figure 4 is a sectional view taken along the line IV—IV of Figure 2.

Figure 5 is a sectional view taken along the line V—V of Figure 2.

Figure 6 is a sectional view taken along the line VI—VI of Figure 5.

Figure 7 is a sectional view taken along the line VII—VII of Figure 2.

Figure 8 is a sectional view taken along the line VIII—VIII of Figure 2.

Figure 9 is a fragmentary plan view of a portion of the underside of the cover showing the position of the interlocking mechanism when the operating handle is in "off" position, and showing in dotted outline the position of the interlocking mechanism when the handle has been moved to cover unlocking position.

Figure 10 is a view similar to Figure 9 but showing the position of the interlocking mechanism when the operating handle is in the "on" position.

Figure 11 is a sectional view taken along the line XI—XI of Figure 1.

Figure 12 is a fragmentary plan view showing the position of various parts when the switch is in contacts engaged position.

Referring to the drawings, the embodiment of 20 the invention, as illustrated, comprises a cabinet 1 having a rectangular box-like sheet metal body portion 2 and a pan-shaped cover 3, of smaller outline than the body portion, hingedly mounted thereon. The cover 3 is adapted to swing to the 25 right in moving to open position. The box 2 is provided, at all four sides, with integral, inwardly directed flanges 4. The edges of the flanges 4 are upwardly bent as at 5 to parallel the sides 6 of the pan-shaped cover 3 as shown in Figure 30 11. Secured to the rear wall 7 of the cabinet 1 and extending forwardly therefrom are mounting posts 8 disposed in pairs adjacent the top and bottom of the cabinet. A metallic U-shaped mounting plate 9 is secured in inverted position 35 to the posts 8 by studs 11. Posts 8 space the plate 9 from rear wall 7 to provide a wiring space for the lead-in wires and prevents their interfering with moving parts within the cabinet. An insulating base 12 of generally rectangular shape, 40 but with a portion 10 projecting from one side, is mounted on plate 9, being disposed thereon near the top thereof and adjacent the right hand edge, as shown in Figure 2. A pair of studs 13, receivable within recesses 14 formed in the top surface of base 12, extend through the bottom of the base 12 and are adapted to be threaded into the face of mounting plate 9 to rigidly secure the base 12 thereto. The insulating base 12 is formed 45 with a plurality of individual compartments 15, 16 and 17 therein and with the central compartment 16 being separated from the other compartments by barrier walls 18 and 19. Within each of the compartments, there is provided a pair of 50 spaced generally L-shaped stationary contact

55 spaced generally L-shaped stationary contact

members 21 and 22, mounted at either end of a compartment.

Figure 8 illustrates the general form of the stationary contact members 21 and 22. Leg 23 of contact member 21 is fitted into a depression in the top wall 24 of the insulating base 12 which prevents its turning out of position. A stud 25 and its cooperating nut 26 secure leg 23 to wall 24. The opposite contact member 22 is maintained in place by having its leg 27 disposed within a depression in wall 28 and with a stud 29 securing it to the wall. A second leg 31 of contact member 21 and a second leg 32 of contact member 22 are each provided with a contacting surface 33, which contacting surfaces are so disposed within a compartment that they lie in the same plane but are spaced from one another. Terminal members 34, 35 and 36 are secured one to each of the stationary contact members 21 by studs 28, and each terminal member carries a terminal stud 31 for securing circuit wires to the switch. Fuse clips 38, 39 and 41 are electrically and mechanically connected one to each of the stationary contact members 22 and by the studs 29. It is to be noted that each stationary contact member 21 and its cooperating terminal member is held in position on wall 24 by one stud 25, and that each of the stationary contact members 22 and its cooperating fuse clip is secured to the opposite wall 28 by one stud 29. A movable elongated insulating switching member or bar 42 is disposed on the insulating base 12. The end walls 43 and 44 of base 12 and the interior barrier walls 18 and 19 are each provided with a recess 45 extending from the top surfaces thereof, which recesses 45 are so located within their respective walls that they will be in horizontal alignment, whereby they are adapted to receive the elongated member 42 to act as a guide therefor, and to confine the movements of this member 42 to a rectilinear path. The recesses 45 are formed to a sufficient depth that when the elongated member 42 is disposed therein, the top surface 46 thereof lies substantially in the plane of the top surface of the insulating base 12. The movable elongated member 42 carries a plurality of movable contact assemblies 47 spaced along the length thereof, there being one of such assemblies disposed within each of the compartments 15, 16 and 17, and each adapted to cooperate with the stationary contact set 21—22 disposed within these compartments to effect the making and breaking of electrical circuits. The movable contact assemblies 47, as shown in Figure 3, each comprise a generally C-shaped member 48 secured to the bar 42 by rivets 49. A bridging contact member 51 is fitted into the space defined by the legs of the C-shaped members 48 and extends beyond either side of this member 48 as shown in Figure 12, to span the contacting surfaces 33 of stationary contact members 21 and 22. A compression spring 52 is likewise disposed within the space bounded by the legs of the C-shaped member 48, with one end of the spring 52 bearing against a leg 53 of C-shaped member 48 and the other end being disposed against the back surface of the bridging contact member 51, and exerts its bias thereupon to normally maintain the contact members 51 in engagement with leg 54 of member 48. Each of the movable contact assemblies 47 are so located within their respective compartments relative to the stationary contact members 21 and 22 that upon movement of the bar 42, in a manner to be hereinafter de-

scribed, to carry a bridging contact 51 into contacts engaged position, the bridging contact 51, upon engagement, will be moved backwardly against the bias of the spring 52 to thereby effect a substantial contact pressure between the movable contact 51 and the stationary contacts 33. A movable contact construction as described provides for the ready self-alignment of the movable contacts 51 when moved into contacts engaged position. As can be seen from Figure 3, the movable contacts 51 will move in a rectilinear path between contacts engaged and contacts disengaged position, and in the construction above described, each of the plurality of movable contacts 51 is adapted to engage and disengage its cooperating stationary contact members 21 and 22 substantially simultaneously as the other movable contacts 51 to thereby make and break a plurality of circuits substantially simultaneously; 5 it is understood that if desired, the movable contact assemblies 47 may be so spaced along bar 42 and so located relative to the various sets of stationary contact members 21 and 22 that one bridging contact member 51 can be brought into 10 contacts engaged position either ahead of or behind another bridging contact member 51, dependent upon which condition is sought to be satisfied. An elongated insulating member 55 is disposed over the movable bar 42, extending the 15 width of base 12 and resting upon the top surfaces of the various walls 43, 44, 18 and 19 of base 12 to close the recesses 45 and to enclose that length of the bar 42 lying within the walls of the base 12. Studs 56 secure the insulating member 55 to base 20 12. A pair of mounting posts 56, internally threaded at both ends, are secured to base 12 adjacent the top edge thereof and disposed one on either side of the center terminal member 36. Each of the mounting posts 56 are disposed for 25 part of their length within recesses provided in the top of wall 24 of base 12. A pair of studs 57 threaded into the bottoms of the mounting posts 56 secure them firmly to the wall 24. An elongated rectangular shaped insulating member 58 30 is mounted on the posts 56 being held thereon by studs 59, which are threaded into the top of the posts 56. The insulating member 58 extends the width of base 12 and forms a roof over the terminal members 34, 35 and 36, and 35 overlaps insulating member 55 which is spaced therefrom. The insulating member 58 lessens the possibility of accidental dislodgment of the terminal members, or of the circuit wires secured thereto, for access to these parts is made very 40 difficult when the insulating member 58 is in place. A generally U-shaped insulating member 61 is disposed about the center fuse clip 39 effectively insulating it from the fuse clips 38 and 41 on either side thereof. The insulating member 61 45 is provided with a pair of projecting portions or prongs 62 which are receivable within recesses in the top surface of base 12 to maintain the insulating member on the base and to assist in readily locating the member on the base and prevent its 50 twisting out of position.

A second insulating base 63 is provided within the cabinet 1, disposed upon the mounting plate 9 and spaced a substantial distance from insulating base 12. A mounting bracket 64 is secured to the plate 9 by studs 65 and to this mounting bracket 64 the insulating base 63 is secured by studs 66. On the top surface of the insulating base 63, a plurality of fuse clips 67, 68, and 69 70 are mounted. Studs 71 secure these fuse clips 75

to the top surface of insulating base 63. These studs 71 also secure a terminal member 72 to each of the fuse clips 67, 68 and 69. Terminal studs 73 are carried by each of the terminal members 72 and are adapted to extend into recesses 74 provided in the top of base 63 to thereby prevent the fuse clips turning out of position. A generally U-shaped insulating member 75 is provided about the center fuse clip 68, and the legs of the U-shaped member 75 will insulate the center fuse clip 68 from the fuse clips 67 and 69 on either side thereof. Stud 73 secures the insulating member 75 to the base 63. The fuse clips 67, 68 and 69 are so arranged upon the insulating base 63 as to vertically align respectively with the fuse clips 34, 35 and 36 whereby each pair of fuse clips cooperate to receive a cartridge type fuse 76, one of which is shown in full line representation in Figures 2 and 4.

Operating mechanism for effecting movement of the movable contact carrying member 42 is provided within the cabinet 1 immediately to the left of the insulating base 12 and embodies a generally U-shaped supporting bracket 77 which is secured to the mounting plate 9 by studs 78 and is indented as at 80 to receive projection 10 of base 12. A post-like member 79 is carried by bracket 77 at the lower end thereof and pivotally supports a member 81. A cotter pin 82 maintains the member 81 on post 79. A rotatable shaft-like member 83 comprising a rectangular block-shaped portion 85 from the bottom face of which projects a cylindrical portion 84, is located at the opposite end of bracket 77. The cylindrical portion 84 extends through the bracket 77 and through an opening in plate 9, directly beneath, to thereby position the member 83 at right angles to the back wall of the cabinet 1. Shaft 83 is maintained in this position by a pair of cotter pins 86 and washers 87 carried by that portion of cylinder 84 disposed between the bracket 77 and the plate 9 which prevents the removal of the member 83. A disk-like member 88 is pivotally disposed upon that portion of the cylinder 84 lying above the bracket 77 and has a second disk 89 secured to the undersurface thereof as by welding. A series of bushings are provided through which the cylinder 84 is adapted to pass. Two of the bushings 91 are formed integral with the disks 88 and 89; another, 90 is formed upon the lower surface of bracket 77. The lower of the bushings 91 spaces the disk 88 above the top surface of bracket 77. Disk 88 is recessed at its periphery as at 92, as seen in Figure 6, for a purpose to be explained. A second disk-like member 93 having a flange portion 94 integral therewith and bent upwardly therefrom is secured, by a stud 95 passing through the flange 94, to the rectangular portion 85 of member 83, and is spaced from the disk-like member 88. A second flange 96 is formed on member 93 and extends downwardly into recess 92 in member 88. Alternate engagement of flange 96 with the opposed defining edges 97 and 98 of recess 92 will effect pivotal movement of the disk member 88 in opposite directions on pivotal movement of disk 83. A generally V-shaped member 99 interconnects the disk member 88 and the pivotal member 81 whereby movement of disk 88 positively effects movement of member 81. The member 99 is pivotally connected to an extension 101 on disk 88 by pin 102, and is pivotally connected to a flange 103 on pivotal member 81 by a pin 104. The supporting bracket 77 is upwardly bent as 78

at 105 and a flange 106 is formed on this bent portion and extends into a recess 107 which, like recess 92, is formed in the periphery of the disk-like member 88. Alternate engagement of the defining edges 108 and 109 of the recess 96 with the flange or stop 106 upon movement in opposite directions limits the extent of pivotal movement of the disk 88 in these opposite directions. Interconnection between disk 88 and the actuating member 81 is effected by an elongated member 111 which is held in pivotal engagement with disk 88 by a pin 112. The opposite end of the connecting member 111 passes through an opening provided in flange 113 formed upon the lower end of pivotal member 81. A compression spring 114 is disposed about the shank portion of the connecting member 111 and is confined between the back surface of the flange 113 and shoulders 115 provided on connecting member 111. The purpose of compression spring 114 will be hereinafter described. Pivotal member 81 carries a pin 116, which pin is closely received within an opening provided at the left hand end of the movable contact carrying bar 42 to thus effect a pivotal connection between the actuating member 81 and the bar 42 and provide a means whereby the bar 42 can be reciprocably moved within recesses 45 to effect engagement and disengagement of the movable contacts 51 with the stationary contacts 33. A winged or slotted member 117 is secured at the top of shaft 83 to the rectangular portion 85 by a stud 118, with the flat wing portions 119 and 121 of the member 117 being disposed in the same plane, and parallel to the bottom wall of the cabinet 1.

An operating handle 122 is rotatably mounted upon the exterior surface of cover 3. The operating handle 122 has formed therewith a shaft 123 which extends through aligned openings in the cover 3 and in the bight 124 of a generally U-shaped bracket 125 disposed on the underside of cover 3. Legs 126 and 127 of the bracket 125 are bent outwardly and are welded to the underside of the cover 3 to secure the bracket 125 to cover 3. A stud 128 threaded into the bottom of shaft 123 prevents the removal of the operating handle 122 from cover 3. An actuating plate 129 of generally triangular shape is rigidly secured to shaft 123 and is movable therewith upon rotation of handle 122, and lies in a plane substantially parallel to the undersurface of cover 3. The plate 129 is provided with a radial slot 131 which receives a pin 132 carried by bight 124 of bracket 125. The pin 132 cooperates with the defining edges of the slot 131 to limit the extent of pivotal movement of plate 129 and of handle 122 in opposite directions. Leg 127 of the U-shaped bracket 125 is bent at one end away from the cover 3 to provide a portion 133 which is spaced from the undersurface of the cover 3. The portion 133 is slotted as at 134 to receive a projecting end 135 of a torsional or overcenter spring 136 whose central portion is coiled; the opposite end 137 of the spring 136 is inserted in an opening 138 provided in a projection 139 provided on the actuating plate 129. Flange 141 bent downwardly from plate 129 is adapted to extend into the space between the wings 119 and 121 of member 117 whereby, upon rotation of the operating handle 122, movement of the winged member 117 is effected for a purpose to be hereinafter fully described. A second downwardly extending flange 142 is provided on plate 129 and serves a purpose also to be hereinafter described.

The exterior surface of cover 3 is marked with the indicia "On," "Off," and "Unlocked" to indicate the operating positions assumed by handle 122. The switching unit within the cabinet 1 will be in circuit closing position when handle 122 occupies the "on" position and will be actuated to break the circuit upon rotation of the handle 122 to "off" position. Movement of the handle 122 to "unlocked" position actuates an interlocking means, to be described, to releasing position to permit cover 3 to be opened. Interlocking means for normally locking the cover 3 to prevent opening thereof in all positions of the operating handle 122 except when this handle is moved to "unlocked" position is provided in the form of the generally triangular-shaped plate 129 and the inwardly directed flange 4 on box 2 cooperating therewith, for plate 129 is adapted, when the cover 3 is closed, to normally continually engage with flange 4 to prevent the cover 3 being opened except when handle 122 is moved to "unlocked" position, in which position plate 129 lies out of engagement with flange 4. Assume the cover 3 closed and the handle 122 in its "on" position, corner 143 of the plate 129 will then be disposed beneath the flange 4 of the box 2, and with flange 4 thus projecting into the path of movement of plate 129, the cover 3 cannot be opened. Figure 9 is a view looking up at the undersurface of cover 3 and illustrates the position of plate 129 when the handle 122 is in "on" position. If the handle 122 were moved to "off" position, a corner 144 of the plate 119 would be located beneath the flange 4 of the box 2, and again flange 4 cooperates with plate 129 to prevent the cover 3 being opened. If the handle 122 were moved to "unlocked" position, it would move the plate 129 to the position shown in dotted outline in Figure 9; in this position both of the corners 143 and 144 would be clear of flange 4 and there would then be no obstruction in the path of movement of plate 129 and, therefore, the cover 3 could be manually rotated to "unlocked" position.

In the movement of the handle 122 between "on" and "off" positions, the line of action of spring 136 is movable across the axis of shaft 123, and the spring 136 will exert its force to maintain the operating handle 122 either in the "off" position or in the "on" position, dependent on which side of shaft 123 the line of action of spring 136 has been moved to. Handle 122 can be made to occupy intermediate positions between "on" and "off" only on the continued application of an external force. On rotation of the handle 122 to "unlocked" position, the handle must be manually held in that position, against the bias of spring 136, until the cover 3 is rotated to open position. If the handle 122 were moved to "unlocked" position and released before the cover 3 were opened, it would be moved to "off" position by the spring 136, for at that moment the spring 136 is exerting its bias to move the handle 122 to the "off" position and thus the cover would be held closed because of the interlocking means.

The handle 122 comprises a hub portion 145 which is slotted at the top as at 146 and has a plurality of apertures 147 in the rim thereof which align with apertures of a cup-shaped element (not shown) disposed within the hub 145 when the handle 122 is in either "on" or "off" position. To lock the handle 122 in either of these positions, it is necessary only to insert a

padlock (not shown) through the proper apertures.

The manner of effecting the operation of the switching unit carried within cabinet 1 will now be described.

Rotation of handle 122 will effect a rotative movement of plate 129, and flange 141 extending from plate 129 will positively engage one or the other of wings 118 or 121, dependent on the direction in which flange 141 is moving, to effect rotation of the winged member 117 in a like direction. Actuation of the winged member 117 will effect a rotatable movement of the shaft 83 to which it is rigidly secured. Now, assuming the various parts to be in the position illustrated in Figures 2 and 6, which is the contacts "off" position, movement of the handle 122 in a counter-clockwise direction from the "off" position to the "on" position will rotate shaft 83 in a like direction to move the disk-like member 93 carried thereon. Flange 96 depending from disk member 93 will be moved from defining edge 98 of recess 92 in the periphery of disk member 88 and into engagement with edge 97 thereof; continued movement of the flange 96 will then effect rotation of disk 88, and disk 88 will move member 99 interconnecting the disk 88 and the pivotal member 81. Member 99 will then positively move the pivotal member 81 about its pivot 19, and the pivotal member 81 having a pin and slot connection with the movable contact carrying bar 42 moves this bar 42 rectilinearly to the right to carry the plurality of movable contacts 51 thereon into engagement with the stationary contact members 21 and 22 to make the electrical circuits controlled thereby. Defining edge 108 of recess 107 on disk 98 will, during the movement of disk 88, be moved until it engages stop 106 and this will prevent any further rotation of the operating handle 122 in counter-clockwise direction and thus define the "on" position of handle 122. Connecting rod 111 secured to disk 93 will, on this movement of the disk 93 effected by the counter-clockwise rotation of the handle 122, be moved to the position of Figure 12 wherein the spring 114 will be compressed between shoulders 115 on rod 111 and the back surface of flange 113 on bracket 17. Disk 88 and member 99 comprise a toggle connection between the rotatable member 88 and the pivotal member 81. Movement of the operating handle 122 to "on" position will move the toggle connecting pin 102 from the left side to the right side of the centerline between the centers of disk 88 and connecting pin 104 to throw the toggle overcenter, and engagement of the defining edge 108 with stop 106 will lock this toggle in the over-set or over-travelled position to thereby lock the movable contact carrying bar 42 in contacts engaged position. Movement of the operating handle 122 in the reverse, or clockwise, direction from "on" to "off" position will effect a reverse movement of the operating parts. Flange 96 on disk 93 will move from edge 97 to edge 98 to effect a positive clockwise rotation of disk 88; and disk 88 will move the end of connecting member 99 pivotally secured thereto by pin 102. As soon as pin 102 is moved to the left of the centerline above described, spring 114, which was compressed on movement of the handle to "on" position, will suddenly expand and will exert force upon flange 113 to effect a snap movement of the pivotal member 81, this snap movement of the pivotal member 81 will be transmitted to the movable contact carrying bar 42

through pin 116 to snap it to the left to effect a snap disengagement between movable contacts 51 and the stationary contact members 21 and 22. When disk 88 is first moved, clockwise, by flange 98, the pivotal member 81 pivots slightly being actuated by the connecting member 99 which, being connected to disk 88 by pin 102, is made to move; movement of the pivotal member 81 will move the bar 42 a slight amount but the movable contacts 51 remain in engagement with the stationary contacts because of bias exerted by springs 52 and will continue to do so until spring 114 is allowed to come into action, whereupon the movable contacts 51 disengage from the stationary contacts with a snap. Engagement of the defining edge 109 of the recess 107 on disk 88 with stop 106 limits the extent of clockwise movement of the operating handle 122 and the various parts moved thereby, and stops the handle 122 in the "off" position. Thus, the defining edges 108 and 109 and the stop 106 act to limit the extent of rotative movement of the operating handle 122 in either direction. And, as was described above, the combination of the pin 132 provided on cover 3 and the radial slot 131 provided in plate 129 also acts to limit the rotative movement of the handle 122 in either direction; in the closed position of the cover, these latter limiting means would be unnecessary for the edges 108 and 109 and the stop 106 would define the "on" and "off" positions of the operating handle, but with the cover open, the pin and slot arrangement is necessary.

If the handle 122 were in the "on" position, indicating that the contacts were engaged, and it was desired that the cover be opened, it would be necessary, as above indicated, to move handle 122 to the position marked "Unlocked" before the cover could be swung open. This movement of the handle 122 to "unlocked" position rotates the plate 129 so that corners 143 and 144 are aligned as to be clear of the flange 4 and thereby removing the obstruction in the path of movement of plate 129. When the handle 122 is moved to "unlocked" position, the toggle 88-99 will be moved just overcenter by rotation of shaft 83 and spring 114 will then become effective and will exert its bias upon flange 113 to move the pivotal member 81 and effect snap disengagement of the contacts as was hereinbefore described, so that before the cover 3 is moved open, the contacts will be disengaged. Upon swinging the cover 3 to open position, the flange 141 will be moved from between wings 119 and 121 and spring 114 can then exert its bias through connecting member 111 upon disk 93 to continue the rotation of shaft 83 to carry the slotted member 117 to the position of Figure 2. With the cover 3 opened, if the handle 122 is then released, it will be rotated by the force of the overcenter spring 136 from "unlocked" position to "off" position, for the force of spring 136 is at the time of release being exerted in a direction which can only move the handle 122 to "off" position.

From the above description, it is apparent the cover 3 cannot be opened while the contacts are engaged for the interlocking means prevents this, and when the cover 3 is opened, it is done so only after the contacts have been actuated to disengaged position. If the contacts were desired to be re-engaged, the cover 3 must first be moved toward closed position and flange 141 must be received in the space between wings 119 and 121; 75

with the handle 122 in "off" position, corner 144 of plate 129 extends over flange 4 and the cover 3 cannot be fully closed; therefore, the handle 122 must be rotated counter-clockwise a sufficient distance that corner 144 clears the innermost edge of flange 4, but with corner 143 held out of obstructing position, whereupon the cover 3 will be able to fully close. Actuation of handle 122 to effect contact movement cannot be had, even though corners 144 and 143 are not in obstructing position unless the door 3 is fully closed, for if the cover were held open even a slight amount, flange 142 and the edges of plate 129 would engage the portion 5 of flange 4 and prevent operating movement of handle 122; and, it is not until the top surface of plate 129 is carried to a position that is below the undersurface of flange 4 that the handle 122 can be rotated as desired and actuation of the movable contacts 51 into engagement with stationary contacts 33 can then be accomplished in the manner hereinbefore described. Once the cover 3 has been opened and it is desired to reclose it, it will always be necessary to have the handle 122 first in its "off" position, for the formations on the operating plate 129 would otherwise be effective to prevent it, that is the flange 141 will not be receivable within the space between wings 119 and 121 but rather would engage the flat upper surfaces thereof; and, further, flange 142 would be disposed outside of the ridge 5 and will rest on the outer surface of flange 4, and either is sufficient to hold the cover open. If inadvertently the winged member 117 were moved by hand or otherwise to the position of Figure 12 which is the contacts engaged position of the switch, while the cover 3 was opened, the cover could not be closed for if the handle 122 were moved to "on" position to align flange 141 with the space between wings 119 and 121, the flange 142 on plate 129 would be disposed outside of ridge 5 and on top of the outer surface of flange 4 and will be engageable with the ridge to prevent the handle being rotated; so, therefore, it will first be necessary to manually actuate winged member 117 to the position of Figure 2 before the device of this invention could be put into operation. Flange 142 has another function in that when the cover is closed and contacts are engaged, it is not possible to move the handle 122 to "unlocked" position, which effects disengagement of the contacts, and open the cover 3 slightly and then actuate the handle 122 back to "on" position to throw the contacts back into reengagement, and this with the cover 3 open, for flange 142 will engage ridge 5 and interfere with rotation of handle 122 until it is moved above the ridge 5, but the flange 142 is of a certain length that by the time it clears ridge 5, flange 141 will be moved out of the space between wings 119 and 121 and, therefore, the interconnection between the handle 122 and the contained mechanism will be broken, and thus the handle 122 can have no effect on the actuation of the contacts when the cover 3 is open.

It is to be noted that with the arrangement of parts as above described, it is possible to effect disengagement of the contacts even though they may have welded together and spring 114 is ineffective to move switch member 42, for the force exerted upon the manual operating handle 122 can be positively transmitted to the switch member 42 to effect movement thereof and the disengagement of the contacts. As described, handle 122 has a positive connection

with the slotted member 117 through flange 141 to effect rotation of the shaft 83; member 83 supported on shaft 83 will engage and move disk 88 through the flange 86, and disk 88 connected to member 81 by the member 88 will move it, whereby member 81 having a pin and slot connection with switch member 42 exerts a positive force thereon to move it to the left. Under normal conditions, member 88 will move member 81 only until pin 102, joining members 88 and 89, passes overcenter, at which time the force exerted by spring 114 will effect the movement of the switch member 42, but with a condition of weld existing spring 114 is ineffective; however, member 88 will continue to move under the force applied by the operating handle 122 and this force will be positively applied by member 81 upon switch member 42 to break the weld between the contacts.

While certain preferred embodiments of the invention have been specifically disclosed, it is understood that the invention is not limited thereto, as many variations will be readily apparent to those skilled in the art and the invention is to be given its broadest possible interpretation within the terms of the following claims.

What is claimed is:

1. In a switching device, an enclosing cabinet, an openable cover therefor, an operating handle on said cover, an electric circuit controlling instrumentality mounted within said cabinet, said electric circuit controlling instrumentality comprising an insulating base, stationary and movable contacts thereon, and a movable switch member for moving said movable contact into and out of engagement with said stationary contact to effect the switching operation, actuating means for effecting movement of said movable switch member, said actuating means comprising a pivotal member operatively connected to said movable member, a rotatable member, toggle means interconnecting said rotatable member and said pivotal member, said toggle means being operative to lock said movable switch member in contacts engaged position, and means interconnecting said operating handle and said actuating means whereby said operating handle can move said actuating means to effect movement of said movable switch member to perform the switching operation.

2. In a switching device, an enclosing cabinet, an openable cover therefor, an operating handle on said cover, an electric circuit controlling instrumentality mounted within said cabinet, said electric circuit controlling instrumentality comprising an insulating base, stationary and movable contacts, and a movable switch member for moving said movable contact into and out of engagement with said stationary contact to effect the switching operation, actuating means for effecting movement of said movable switch member, said actuating means comprising a pivotal member operatively connected with said movable member, a rotatable member, toggle means interconnecting said rotatable member and said pivotal member, said toggle means being operative to lock said movable switch member in contacts engaged position, and means interconnecting said operating handle and said actuating means whereby said operating handle can move said actuating means to effect movement of said movable switch member to perform the switching operation, and resilient means actuatable on said pivotal member to effect snap move-

ment of said movable switch member in one direction.

3. In an enclosed switch, an enclosing cabinet, an openable cover therefor, an operating handle thereon, a switching device mounted within said cabinet, said switching device comprising an insulating base, stationary and movable contacts therein, a switching member for effecting movement of said movable contact into and out of engagement with said stationary contact, actuating means for moving said switching member to perform the switching operation, said actuating means comprising a pivotal member operative on said switching member for movement thereof, a shaft rotatably supported upon a wall of said cabinet, a first member supported on said shaft, means interconnecting said first member and said pivotal member whereby the former can actuate the latter, a second member supported on said shaft, and means effecting a resilient interconnection between said second member and said pivotal member and operative to effect a snap movement thereof, a movable member disposed within said cabinet, spaced from said actuating means and movable by said operating handle, and means carried by said movable member to effect a separable connection between said movable member and said actuating means for the switching member whereby said operating handle can effect movement of said actuating means to move the switching member to effect the switching operation.

4. In an enclosed switch, an enclosing cabinet, an openable cover therefor, an operating handle thereon, a switching device mounted within said cabinet, said switching device comprising an insulating base, stationary and movable contacts therein, a switching member for effecting movement of said movable contact into and out of engagement with said stationary contact, actuating means for moving said switching member to perform the switching operation, said actuating means comprising a pivotal member operative on said switching member for movement thereof, a shaft rotatably supported upon a wall of said cabinet, a first member supported on said shaft, means interconnecting said first member and said pivotal member whereby the former can actuate the latter, a second member supported on said shaft, and means effecting a resilient interconnection between said second member and said pivotal member and operative to effect a snap movement of said pivotal member, an operating member mounted on the interior surface of said cover and movable by said operating handle, a slotted member carried by said shaft, means extending from said operating member and receivable within the slot of said slotted member to provide a separable connection between said operating member and said slotted member whereby said operating handle can move said actuating means to move the switching member.

5. In an enclosed switch, an enclosing cabinet, an openable cover therefor, an operating handle thereon, a switching device mounted within said cabinet, said switching device comprising an insulating base, stationary and movable contacts therein, a switching member for effecting movement of said movable contact for cooperation with said stationary contact, a pivotal member operatively connected to said switching member for movement thereof to perform the switching operation, a shaft-like member rotatably supported upon a wall of said cabinet, a first mem-

ber supported on said shaft, means interconnecting said first member and said pivotal member whereby the former can actuate the latter, resilient means operative to effect a snap movement of said pivotal member, an operating plate-like member mounted on the interior surface of said cover and disposed substantially parallel thereto, said plate-like member being movable by said operating handle, a flange on a side wall of said cabinet cooperating with said plate-like member to retain the cover closed in all positions of said

5 operating handle except one predetermined position, a slotted member carried by said shaft, means extending from said operating member and receivable by the slot of said slotted member to effect a separable connection between said plate-like member and said slotted member whereby said operating handle can move said pivotal member to effect movement of said switching member.
